Specification of Letters Patent. Patented Mar. 26, 1918.

Application filed September 16, 1915. Serial No. 50,983.

To all whom it may concern:

Be it known that I, ELMER E. LANE, a citizen of the United States, residing at Beverly, in the county of Essex and State of Massachusetts, have invented certain new and useful Improvements in Skiving-Machines; and I do hereby declare the following to be a full, clear, and exact description of the invention, such as will enable others skilled in the art to which it appertains to make and use the same.

This invention relates to skiving machines and more particularly, to a blank feeding device for machines adapted to skive box toes and counters for boots and shoes.

Certain types of machines for skiving box toe and counter blanks employ a cavity roll or movable matrix to position the blank while it is being skived. The cavity in which the blanks are held has approximately the shape of the died-out blanks, so that it is necessary to accurately position the blank over the cavity while it is being skived. When the machine is in operation, the blanks are automatically presented to the cavity by a feeding device which moves in timed relation to the movement of the cavity roll or matrix. It is often desirable to stop the feeding device while the skiving mechanism continues to operate, to fill the blank magazine, and for various other reasons. Upon restarting the feeding device while the skiving mechanism continues to operate, if the feeding device makes a partial feed stroke, a blank may be presented in untimed relation to the skiving mechanism, so that the blank will be spoiled or the machine may be injured.

The primary object of the present invention is to provide a blank feeding device for a skiving machine which will insure that the blanks will be fed in timed relation to the operation of the matrix or die roll.

In accordance with this object, one feature of the invention contemplates the provision in a skiving machine having a blank feeding device, of means for connecting the feeding device with its actuating mechanism, and means movable in timed relation to the movement of said mechanism for locking the connection of the feeding device with its actuating mechanism and for controlling the release of said connection.

While the illustrated embodiment of the invention is shown as a feeding device for

a skiving machine, the feeding device is not, however, limited to use in a skiving machine but may be employed in any machine in which blanks are intermittently fed and in which the feeding device is started and stopped while the machine for treating the blanks continues in operation.

In the skiving machine illustrated in my co-pending application Serial No. 866,064, filed October 10, 1914, the blank feeding device is arranged to be disconnected from its actuating mechanism automatically by means operated through the blanks in the magazine, and by a foot treadle, the automatically operated means is controlled to disconnect the feeding device from its actuating mechanism at the time when the feeding device completes its feeding movement; but the feeding device may be disconnected from its actuating mechanism by the treadle at any time.

In the preferred form of the present invention, the disconnection of the feeding device from its actuating mechanism by the foot treadle is limited to the time when the feeding device completes its feeding movement. Accordingly, another feature of the invention contemplates the provision in a skiving machine having a blank feeding device and actuating mechanism therefor, of means to connect the feeding device with its actuating mechanism, means under the control of the operator to release the connection of the feeding device with its actuating mechanism, and means to permit operation of the releasing means to disconnect the feeding device from its actuating mechanism only at a predetermined point in the cycle of operation of the machine.

These and other features of the invention will appear from an inspection of the accompanying drawings and the following detailed description of the construction and operation of the machine illustrated therein.

In the drawings, Figure 1 is a view in side elevation of a leather skiving machine embodying the preferred form of the invention; Fig. 2 is a vertical sectional view of the upper portion of the machine showing the feeding device and its actuating mechanism; Fig. 3 is a side elevation; Fig. 4 is a plan view; and Fig. 5 is a front elevation showing in detail the feed locking latch and its locking device.

The machine illustrated in the drawings

is substantially the same in construction, arrangement and mode of operation of its various parts as the machine disclosed in the patent to Scott No. 969,987, patented 5 September 13, 1910. In this machine the blanks to be treated are placed in a vertical stack in a magazine 12 and pressed against a bedplate 14 by a follower 16. The blanks are fed one at a time by a feed slide 18 which 10 advances the blanks to the bite of a pressure roll 20 and a die roll 22 which has a blank positioning die cavity 24. The operation of the rolls advances the blanks against a skiving knife 26 which has its cutting edge between the rolls at a point approximately 15 opposite the point of contact of the rolls with the blank. The machine is designed to skive one blank for each revolution of the rolls, and the feed slide makes a complete 20 reciprocation in timed relation to the rolls and presents the blank to the rolls so that it will register with the die cavity 24. The feed slide is actuated by means of a feed lever 28 connected with a yoke 30 which is 25 oscillated by means of a cam on the main drive shaft. The feed lever and feed slide are connected and disconnected during the continuous operation of the skiving mechanism by raising and lowering the lever 28. 30 When the lever is raised, a slot 32 on its upper side engages a pin 34 on the bottom of the feed slide, and the feed lever and slide are connected to move in unison. The feed lever is raised and lowered by a foot treadle 36 with which the lever is connected by a 35 distance arm 38 having a roller 40, a link 42, a lever 44, and a link 46. When the treadle has been moved down to connect the feed slide with the lever 28, the treadle is 40 held in its lowered position by means of a latch 48, and when the treadle is released from the latch, it is automatically raised by the spring 49, thereby disconnecting the feed lever and feed slide. The construction described above is substantially the same as 45 that of the patent hereinbefore referred to.

During the operation of the machine, the rolls rotate continuously and the feed lever is reciprocated continuously. The feed slide 50 cannot be disconnected from the feed lever during the forward or feeding stroke, even when the feed lever is lowered by the treadle, because an abutment 50 on the feed lever will carry the feed slide to the end of its 55 feeding movement and leave it there. However, if the feed lever is lowered during the back or return stroke of the feed slide, the slide will be disconnected from the feed lever and left in the place it happens to be 60 when the feed lever is lowered. Since the feed lever continuously reciprocates, its next forward movement will carry the feed slide to the end of its feeding movement. Should the feed slide be disconnected in a position 65 far enough back on its return stroke so that

blanks in the magazine could come in contact with the bedplate, the next forward stroke of the feed slide would tend to carry the blank into the feed rolls in an untimed relation to the movement of the rolls and 70 mutilate the blank, or the blank might be clamped between a gate 52 and the slide 18. To avoid the feeding of blanks in untimed relation to the operation of the skiving mechanism, the latch 48 is locked from 75 movement during the return stroke of the feed slide so that the treadle 36 cannot be moved to disconnect the feed lever from the feed slide during its return stroke. The latch is unlocked only when the feed slide 80 is approximately at the end of its feeding stroke so that the feed slide may be disconnected at the end of its feeding stroke. Since the feed slide can only be disconnected at the end of the feeding stroke, its connection 85 will be made at this point, which will insure that the feed slide will present a blank in timed relation to the movement of the skiving rolls because the feed slide will make a 90 complete return and feeding stroke in presenting the blank.

The lock for preventing movement of the latch is mounted on a bracket 54 which is attached to the machine frame directly above the latch 48. A locking lever 56 is pivotally 95 mounted on a stud 58 in the bracket 54 and has an abutment pin 60 which is adapted to swing over a cam 62 on the upper side of the latch 48. A ratchet arm 64 is pivotally mounted on the stud 58 beneath the locking 100 lever and is connected by a link 66 with an arm 68 mounted on the end of the feeding cam shaft 70. The shaft 70 continually oscillates the ratchet arm 64 in timed relation to the movement of the feed slide, and during the feeding stroke of the feed slide the ratchet arm and locking lever 56 are connected and moved together. The ratchet arm carries a spring pressed pawl 72 which is mounted in a position to engage a tooth 110 74 projecting from the side of the locking lever 56 and lock the lever to the ratchet arm for movement therewith. The ratchet arm makes a connection with the locking lever when the feed lever 28 is at the end 115 of its return stroke, as shown in Fig. 1, and the movement of the ratchet arm during the feeding stroke of the feed lever carries the locking lever across the cam 62 and brings the locking lever to an unlocking position 120 just before the feed lever 28 is at the end of its feeding stroke; this position is shown in Fig. 3. When the locking lever is in this position, the latch 48 can be moved to release the foot treadle 36. Upon the completion of the feeding stroke, the ratchet arm is moved to bring a tail 76 on the pawl 72 into engagement with a set screw 78, mounted in a boss 80 on the bracket 54, to disconnect the pawl from the tooth 74 and permit 125 130

the locking lever 56 to swing back against a set screw 82 mounted in a boss 84 on the bracket 54. When the locking lever is released from the pawl 72, it is quickly moved 5 back against the set screw 82 by means of a spring 86 which is mounted in a boss 88 on the lower face of the releasing lever 64. With this construction, the locking lever is 10 in locking position over the latch 48 during the greater part of the reciprocation of the feed slide, and is quickly moved back into locking position at the end of the feeding stroke. The arm 68 has a bolt and slot connection with the link 66 which permits an 15 adjustment to vary the amplitude of oscillation of the ratchet arm, and the set screw 78 can be adjusted to vary the time in which the pawl 72 will be moved to release the locking lever. This adjustment permits the 20 locking device to be accurately timed with relation to the movement of the feed slide.

The latch 48 is provided with a foot treadle 90 by which it may be manually operated to release the treadle 36 when the 25 locking lever is in the position shown in Fig. 3. In addition to the manually operated means for actuating the latch 48 in releasing the treadle 36, the latch is also provided with an automatically operated means for 30 releasing the treadle 36 which is controlled by the movement of the blanks in the magazine. The follower 16 presses on the stack of blanks in the magazine and moves down with them as the blanks are fed from the bottom. When the blanks in the stack have 35 been reduced to a predetermined number, the follower 16 is arranged to engage the latch releasing mechanism and place it in condition to release the latch 48 from the treadle 40 36, but the latch 48 will not be moved into releasing position until the feed slide has reached the end of its feeding stroke. To this end, the latch 48 is connected by a rod 45 92 with a stop lever 94 mounted on the machine frame above the magazine. As the follower 16 moves down, a pin 96 at its upper end engages the lever 94 and tends to raise the rod 92. If the locking lever 56 is in the position shown in Fig. 3, the rod 90 will 50 be raised and the latch 48 disconnected from the foot treadle 36. If, however, the locking lever 56 is in position over the cam 62, the latch cannot be moved and the action of the pin 96 on the lever 94 will distend a 55 yielding section 98 in the rod 92 and hold it under tension until the locking lever 56 has been moved to the position shown in Fig. 3. Then the latch will be automatically raised by the spring of the section 98 and the movement of the lever 94, to release the treadle 36.

The latch 48 has a pawl 100 pivotally mounted on its side (Fig. 3), which is adapted to engage an adjustable abutment 102 on the treadle 36 when the treadle is 60 moved down to connect the feed lever 28

with the feed slide. The pawl 100 is yieldingly mounted between a lug 104 on the latch 48, and a spring 106 mounted in a boss 108 opposite the lug 104. With this construction, the treadle 36 can be moved down 70 at any time to raise the feed lever for connection with the feed slide. When the treadle 36 has been moved down, it will be held by the latch, and the latch cannot be moved to release the treadle until the feed 75 slide has nearly reached the end of its feeding stroke, at which time the latch is unlocked.

Having thus described the preferred form of my invention, what I claim as new is:— 80

1. Blank feeding mechanism for skiving machines comprising, blank feeding means, actuating mechanism for said feeding means, means to connect the feeding means with its actuating mechanism, means under 85 the control of the operator to release the connection of the feeding means with its actuating mechanism, and means to permit the operation of the releasing means for disconnecting the feeding means from its actuating mechanism only at a predetermined 90 point in the cycle of operation of the machine.

2. Blank feeding mechanism for skiving machines comprising, blank feeding means, 95 actuating mechanism for said feeding means, manually operated means and automatically operated means for disconnecting the feeding means from its actuating mechanism, and devices for permitting the operation of the disconnecting means to stop the feeding of blanks only at a predetermined 100 point in the cycle of operation of the machine.

3. Blank feeding means, actuating mechanism for the feeding means, means for connecting the feeding means with its actuating mechanism, devices for maintaining the connection of the feeding means and its actuating mechanism and a lock for controlling 105 the operation of the maintaining devices.

4. Blank feeding mechanism for skiving machines comprising, means for supporting a stack of blanks, means for feeding blanks 115 from the stack, means to actuate the feeding means, means controlled by the movement of the blanks in the stack to automatically stop the actuation of the feeding means, manually operated means for stopping 120 the actuation of the feeding means, and devices to limit the operation of said stopping means to a predetermined period in the cycle of operation of the machine.

5. Blank feeding mechanism for skiving 125 machines comprising, blank feeding means, actuating mechanism for the feeding means, means for connecting the feeding means with its actuating mechanism, and means movable in a timed relation to the move- 130 0

ment of said mechanism for locking the connection of the feeding means with its actuating mechanism and for controlling the release of said connection.

- 5 6. Blank feeding mechanism for skiving machines comprising, a feed slide for feeding blanks, actuating devices for the feed slide, means for connecting the feed slide with its actuating mechanism, a latch for 10 maintaining the connection between the feed slide and its connecting means, and a lock for controlling the movement of said latch.

7. Blank feeding mechanism for skiving machines comprising, a reciprocating feed 15 slide for supplying blanks, means for actuating the slide, means for connecting the slide with the actuating means, a latch for maintaining the connection of the feed slide with its actuating means, a lock for said 20 latch, and connections between the actuating mechanism and the lock for moving the lock into position to permit a disconnection of the feed slide from its actuating mechanism at a predetermined point in its cycle 25 of operation.

8. Blank feeding mechanism for skiving machines comprising, a magazine for supporting a stack of blanks, a follower for engaging the outer blank of the stack, a reciprocating feed slide for supplying blanks from the magazine to the skiving mechanism, means for actuating the feeding means, means for connecting the feeding means with its actuating means, a latch for 30 maintaining the connection of the feed slide with its actuating means, connections between the latch and the follower, and a lock for the latch.

9. Blank feeding mechanism for skiving 40 machines comprising, a magazine for supporting a stack of blanks, a follower for pressing the stack of blanks, a feed slide for supplying blanks from the stack to the skiving mechanism, actuating devices for the feed slide, means for connecting and disconnecting the feed slide and its actuating 45

devices, a latch for locking the feed slide to said actuating devices, a lock for said latch to prevent disconnection of the feed slide and actuating devices, a connection between the latch and the follower, a connection between the lock and actuating devices for the feed slide for moving the lock in a definite relation to the feed slide, and means for preventing an operation of the latch until the lock has been moved to a predetermined position.

10. Blank feeding mechanism for skiving machines comprising, blank feeding means, means for actuating the feeding means, devices for connecting the feeding means with its actuating means, a latch for maintaining the connection of the feeding means with its actuating means, a lock normally held in locking position upon said latch, and a member on said latch movable while the latch is locked, to allow the connection of the feeding means with its actuating means.

11. Blank feeding mechanism for skiving machines comprising, blank feeding means, means to actuate the feeding means, devices for connecting the feeding means with its actuating means arranged to set and lock said devices in feeding position at any period in the cycle of operation of the machine, and means to limit the unlocking of said devices to a predetermined period in the cycle of operation of the machine.

12. Blank feeding mechanism for skiving machines comprising, a magazine for supporting a stack of blanks, a reciprocating feed slide for intermittently feeding the blanks from the magazine to the skiving mechanism, means for actuating the slide, manually and automatically operated means for disconnecting the slide and its actuating means during the operation of the machine, and devices for controlling the disconnecting means to prevent the disconnection of the feed slide and its actuating mechanism during the return stroke of the feed slide.

ELMER E. LANE.
